UNITED STATES PATENT OFFICE.

FREDERICK M. STEVENS, OF WATERBURY, CONNECTICUT, ASSIGNOR TO VEROFORM HYGIENIC COMPANY, A CORPORATION OF NEW YORK.

SOAP-DISPENSER.

No. 899,812.

Specification of Letters Patent. Patented Sept. 29, 1908.

Application filed February 21, 1908. Serial No. 417,040.

To all whom it may concern:

Be it known that I, FREDERICK M. STEVENS, a citizen of the United States, residing at Waterbury, in the county of New Haven and State of Connecticut, have invented certain new and useful Improvements in Soap-Dispensers, of which the following is a full, clear, and exact description.

My invention relates to soap dispensers, particularly of that type in which a quantity of liquid soap or compound is stored in a vessel or receptacle provided with means for suitably discharging small quantities when desired.

It is the purpose of my present invention to improve and simplify apparatus of this class, and attain the discharge of the soapy liquid in as convenient and positive a manner as possible. For this purpose, I make use of a submerged cup or cylinder within the soap receptacle from which the fluid is discharged upward through a hollow depressible plunger coöperating therewith. I also provide for very quick and easy assembling or disassociation of all the operating parts.

With these and other objects in view, my invention consists in the features of construction and combination as hereinafter set forth and claimed.

In the drawings: Figure 1 is a side elevation of a soap dispenser embodying the principles of my invention; Fig. 2 is a vertical sectional view of the same; Fig. 3 is a detail side view of the plunger or piston and its allied parts; and Fig. 4 is a detail side view of the cup or cylinder with which the plunger or piston coöperates.

Referring to the drawings in which like parts are designated by the same reference sign, 1 designates a receptacle or vessel conveniently made of glass, and inset in, or otherwise attached to, a supporting base 2.

3 designates the cover of the receptacle, which is removable in any desired way, for example, by virtue of a frictional or sliding engagement 4, as shown.

5 designates a central opening within the cover from which there projects downwardly a sleeve 6, preferably formed integral with the cover and having a round cylindrical interior guiding surface 7.

8 designates a lug or projection on the interior surface of the sleeve 6. This sleeve and lug exercise a guiding function on the

fluid expelling plunger, as hereinafter described.

Extending downwardly from the cover 3, I provide a skeleton supporting frame or shell 9, at the lower end of which is formed or provided a cup or cylinder 10. This cup or cylinder is entirely closed at its lower end 11, but is open at its upper end at a plurality of notches, holes or recesses 12, which are open or uncovered in the normal condition of the apparatus.

13 designates a piston or plunger movable in the cylinder 10, and having an upwardly extending tubular piston rod 14, which extends through the cover 3. This piston or plunger is soldered or otherwise fixed to a rounded knob or handle 15, normally above or beyond the plane of said cover.

16 designates a cylindrical guiding surface preferably forming part of the knob 15, and which coöperates with the interior surface 7 of the sleeve 6. I have illustrated a convenient construction of the part 16 adapted to permit an easy removal of the plunger. Along a vertical element of the cylindrical surface 16, I form a deep depression 17 adapted to fit over the projection 8.

18 designates a recess extending laterally from the groove 17, and terminating in a vertical recess 19 of limited and predetermined vertical extent, corresponding to the desired throw or travel of the plunger. The plunger is assembled in operative relation by engaging the groove 17 over the projection 8 by a manipulation analogous to the engagement of a bayonet joint, until the projection lies in the vertical groove 19 where it exercises its normal guiding function to limit the vertical displacement of the plunger and prevent angular movement thereof. The plunger is normally impelled to its upper limit of movement by a spring 20, or in any convenient way, so that the notches or holes 12 of the cylinder 10 are uncovered. In practice, I provide a spout or discharge orifice 21, extending laterally and downwardly from the knob or handle 15, but it is evident that any suitable passages or orifices may be provided for this purpose.

The operation is as follows: Under normal conditions the relation of the parts is as shown in Fig. 2 with the holes or notches 12 of the cylinder 10 uncovered by the plunger. Under these circumstances the liquid

soap or compound in the receptacle 1 flows into and fills the interior of the cylinder 10, any air which may be contained therein escaping upward through the hollow plunger. If now a quantity of the soapy compound is desired, it is merely necessary to depress the knob or handle 15, and the contents of the cup or cylinder 10 will be discharged upward through the hollow piston rod 14, and into said knob or handle from which it may escape through any suitable discharge orifice such as the laterally and downwardly extending passage 21. When the pressure on the knob or handle is released, the plunger rises to its normal position, and a new charge enters the cup or cylinder 10 which may be likewise expelled until the desired quantity of soapy fluid is obtained. The capacity of the cup or cylinder 10 is, however, such that a single depression of the plunger discharges or expels a quantity of the soapy fluid adequate for ordinary needs.

What I claim is:—

1. In a soap dispenser, a receptacle, a cover having a depending circumferential

flange fitting over said receptacle and having a central integral guiding sleeve with an interior lug, a cup or cylinder within said receptacle and having notches on its upper edge, and a hollow plunger co-operating with said cup and having a vertical recess of limited vertical extent engaging said lug, whereby the vertical movement of the plunger is limited to a predetermined throw. 30

2. In a soap dispenser, a receptacle, a cover having a guiding sleeve with an interior lug, a cup or cylinder within said receptacle, and a plunger having a cup shaped knob with a vertical groove embossed integrally inward on one side and communicating with a lateral and a vertical recess in said knob and adapted to engage over said lug, whereby the plunger is made removable without weakening the structure of said 45 knob. 35

In witness whereof, I subscribe my signature, in the presence of two witnesses.

FREDERICK M. STEVENS.
